US00D820129S

(12) **United States Design Patent** (10) Patent No.: **US D820,129 S**
Kreitzer et al. (45) Date of Patent: ** Jun. 12, 2018

(54) **FRONT PANEL FOR A MEASUREMENT INSTRUMENT**

(71) Applicant: **Tektronix, Inc.**, Beaverton, OR (US)

(72) Inventors: **Robert R. Kreitzer**, Tigard, OR (US); **Gary J. Waldo**, Hillsboro, OR (US); **Kenneth P. Dobyns**, Beaverton, OR (US); **Mark A. Briscoe**, Portland, OR (US); **Michael J. Wadzita**, Vancouver, WA (US); **Pechluck S. Laskey**, Portland, OR (US); **Jared Randall**, Seattle, WA (US); **Jordan P. Evans**, Seattle, WA (US); **Joshua M. Kornfeld**, Seattle, WA (US); **Jonah S. Griffith**, Seattle, WA (US); **Phelan W. Miller**, Seattle, WA (US)

(73) Assignee: **Tektronix, Inc.**, Beaverton, OR (US)

(**) Term: **15 Years**

(21) Appl. No.: **29/603,725**

(22) Filed: **May 11, 2017**

Related U.S. Application Data

(60) Continuation of application No. 29/562,905, filed on Apr. 29, 2016, which is a division of application No. 29/509,914, filed on Nov. 21, 2014.

(57) **CLAIM**

The ornamental design for a front panel for a measurement instrument, as shown and described.

DESCRIPTION

FIG. 1 is a front left perspective view of a test and measurement instrument incorporating the ornamental design of the front panel.

FIG. 2 is a front right perspective view of the front panel for a measurement instrument of FIG. 1.

FIG. 3 is a front elevation view of the front panel for a measurement instrument of FIG. 1. FIG. 3A is an enlarged view of the arrangement of the controls of the front panel for a measurement instrument of FIG. 1.

FIG. 4 is a right-side elevation of the front panel for a measurement instrument of FIG. 1.

FIG. 5 is a left-side elevation of the front panel for a measurement instrument of FIG. 1.

FIG. 6 is a top plan view of the front panel for a measurement instrument of FIG. 1; and,

FIG. 7 is a bottom plan view of the front panel for a measurement instrument of FIG. 1.

The portions of the front panel for a measurement instrument shown in broken lines form no part of the claimed design.

1 Claim, 6 Drawing Sheets
